UNITED STATES PATENT OFFICE.

PATRICK GOODMAN, OF NEW YORK, N. Y.

EXCAVATING-MACHINE.

1,326,337.

Specification of Letters Patent.

Patented Dec. 30, 1919.

Application filed June 28, 1919. Serial No. 307,343.

To all whom it may concern:

Be it known that I, PATRICK GOODMAN, a citizen of the United States, and a resident of New York city, in Bronx county and 5 State of New York, have invented certain new and useful Improvements in Excavating-Machines, of which the following is a full, clear, and exact description.

Among the principal objects which the 10 present invention has in view are: to provide an excavating tool which automatically disposes itself to prevent the contents of the tool from spilling as the tool is lifted; to provide an apparatus readily disposed in 15 convenient form for transportation or storage; to regulate the digging capacity of the tool; and to control the depth of the operation of the tool.

Drawings.

20 Figure 1 is a side elevation of an apparatus constructed and arranged in accordance with the present invention, the digging bucket of the apparatus being shown in position to receive a load.

Fig. 2 is a similar view showing the bucket in partially raised position.

Fig. 3 is a similar view showing the bucket in its fully raised position.

30 Fig. 4 is a front elevation of the apparatus in the position disclosed in Fig. 3.

Fig. 5 is a side elevation showing the apparatus in the position in which the bucket is dumped.

35 Fig. 6 is a front elevation of the apparatus on diminished scale showing the hoisting boom and parts connected therewith, laterally disposed, as when dumping the bucket at the side of a trench.

Description.

40 As seen in the drawings, a short mast 11 is pivotally stepped in a foot block 12 and in a cross head 13. The foot block 12 is suitably mounted on a platform 14. Secured to the platform 14 for bracing the cross head 13, are stiff legs 15 and 16. The platform 14 as shown in the drawings is movably mounted on rollers 17. The rollers 17 are 50 employed when a track or other preferable runway is furnished.

The mast 11 is rotated by means of a bull wheel 18. The bull wheel 18 is fixedly secured to the mast 11, and has a hinge block 55 19 to form a bearing for the butt-end of the

boom 20 and the pin 21, which pivotally unites the said boom and block 19.

The boom 20, as shown in Fig. 4 of the drawings, is constructed of two channel bars 22 which are bolted at the outer extremity to the spacing block 23, and at the inner end to the lugs 24. The block 23 has an opening 25 formed therethrough to hold the sheave 26, around which is rove the cable 27, by which a dipper stick 28 is manipulated.

The dipper stick 28 is preferably constructed from two rack bars 29. The rack bars 29 are held in spaced relation by the bolting block 31. The guide block 31 extends across the back edge of the bars 28 and supports a pin 32 and sprocket wheels 33, the teeth whereof mesh with the teeth of the bars 29. The pin 32 also serves as a bearing for a brake wheel 34, about which the brake band 35 is passed. The brake band 35 is contracted or expanded upon the wheel 34 by a nut 36 and a lever 37, operatively connected therewith. The lever 37 is engaged by a flexible cable 38 that is led over suitable guides to the base of the mast 11. By this arrangement, whenever the cable 38 is pulled taut, the extension of the dipper stick 28 is fixed, as hereinafter more fully set forth.

35 The bucket 39 is pivotally suspended by means of a fixed bail 40 and pivot pins 41 therefor, at the free end of the dipper stick. The pins 41 are set in the bucket 39 off center, or so that the weight of the bucket 39 and of the load carried thereby rocks the said bucket on the pins 41 until the stop 42 on the side of the bucket engages the edge of the bail 40. In this position the plow-points 43 are vertically disposed as seen best in Figs. 2 and 3 of the drawings.

45 The bucket 39 is dumped by means of the flexible line 44. The line 44 is rove over the sheaves 45, 46 and 47, the latter being mounted on the foot block 12.

With an apparatus constructed as above described the operation is as follows:

The platform 14 and superstructure mounted thereon, together with the mast 11, being placed in position on the rollers 17, 105 or their equivalent, the boom 20 is lowered to the position shown in Fig. 1 by paying out the supporting cable 48. The boom 20 being extended, the dipper stick 28 and bucket 39 mounted thereon are loaded by 110

slackening the cables 27 and 44. When the bucket 39 engages the ground, either at the surface or at the bottom of the trench to be formed, it is drawn toward the platform 14 by means of the cable 44 so that the plow-points 43 dig into the earth to loosen the same for delivery within the interior of the bucket 39.

If desired, the initial operating position 10 of the bucket 43 is extended beyond the end of the boom 20. This is accomplished by permitting the dipper stick 28 to roll on the sprocket wheels 33 until said dipper stick is fully extended. In this position the cable 15 38 is drawn taut to hold the band 35 tightly on the pulley 34. This does not prevent the swing of the dipper stick around the pin 32, when the cable 27 is drawn to swing the bucket-carrying end of the dipper stick toward the pulley 26 and the outer end of the boom 20. In this position it will be observed for all intents and purposes, the dipper stick is an extension of the boom 28. This is the position which the apparatus 20 usually assumes when starting excavation of 25 a trench.

If, now, the cable 44 is drawn upon, it will be seen that the plow-points 43 are forced into the ground to loosen the same so that 30 the bucket 39 may gather it. Care should be exercised in starting the trench that the brake band 35 should be partially released to permit the dipper stick 28 to rise between the channel bars 22 of the boom 20 during 35 the recession of the bucket 39.

When the bucket 39 with its load has been drawn into the position shown in Fig. 2, the cable 48 is drawn upon to lift the boom to the position shown in Fig. 3. During this 40 operation, the cable 44 is slackened and the weight of the bucket 39 and contents thereof being off center from the pins 41, the bucket 39 retains its upright or holding position. When the bucket and dipper stick have 45 reached the position shown in Fig. 3, the mast 11 is turned by drawing on the bull wheel 18. At the same time that this is done, the cable 27 is drawn to lift the dipper stick and load carried thereby, to an elevated 50 position.

After the mast has been rotated, the boom 20 is partially lowered to the position as shown in Fig. 6, in which position the bucket 39 swings away from the boom 20, 55 and the bail 40 is placed in the horizontal position where the center of gravity of the bucket 39 being unsupported the bucket is automatically dumped.

It will be understood that as the dipper 60 stick 28 assumes the position shown in Figs. 5 and 6 of the drawings, the stop 42 prevents the bucket 39 swinging and holds the same in fixed relation to the said bail 40, until the center of gravity of the bucket 65 39 and load carried thereby, passes to the free

side of the pins 41, when being unsupported, the bucket swings to the dumping position.

It will be understood that if the bucket should, for any reason, become jammed, it may be rocked to the dumping position by 70 manipulating the cable 44, which will pull the bucket into position where the center of gravity is unsupported.

The boom 20 and the dipper stick 28 are preferably constructed of heavy material, 75 the purpose being that where necessary or advantageous, the full weight of the boom and the dipper stick will be imposed upon the bucket 39. To do this the brake band 80 35 is tightened on the brake pull 34 and held until it is desired to relieve the bucket of the weight of the boom and dipper stick.

As the operation of digging the trench progresses, the platform, and parts carried thereby, are moved away from the open cut 85 and the digging operation of the apparatus is continued. When the trench is completed, the various pivot pins connecting the boom 20 with the mast 11, and the dipper stick 28 with the boom 20 are removed and the 90 parts are in position for cartage separately. The bucket 39 may also be removed from the stick 28 and the stiff legs 15 and 16 may be removed from the platform 14 to 95 permit the mast 11 to be unstepped from the block 12, and the whole to be disposed in convenient form for cartage.

Claims:

1. A machine as characterized comprising 10 the combination of a dig bucket; a dipper stick pivotally connected thereto by a rigid bail and pivot members, said pivot members being disposed on said bucket adjacent one side thereof; stop members set out 10 from said bucket for engaging said bail to prevent the bucket from turning on its pivot through said bail in one direction; and means attached to the side of said bucket removed from said pivot members for draw- 11 ing said bucket toward its work.

2. In a machine as characterized the combination of a stiff dipper stick; a supporting boom therefor; a rigid bail extended from the end thereof; a dig bucket having 11 an open end and digging members adjacent thereto, said bucket being pivotally mounted in said bail to rotate therethrough and arrested by engagement therewith to be thereafter supported with the center of 12 gravity at one side of said bail when said dipper stick is in approximately vertical position; and means for lifting said dipper stick to horizontally extended position for permitting the bucket to rotate on its pivot 12 through said bail for inverting said bucket.

3. In a machine as characterized the combination of a stiff dipper stick; a supporting boom therefor; a rigid bail extended from the end thereof; a dig bucket having 13

an open end and digging members adjacent thereto, said bucket being pivotally mounted in said bail to rotate therethrough and arrested by engagement therewith to be thereafter supported with the center of gravity at one side of said bail when said dipper stick is in approximately vertical position; means for lifting said dipper stick to hori-

zontally extended position for permitting the bucket to rotate on its pivot through 10 said bail for inverting said bucket; and means for moving said dipper stick and bucket connected therewith vertically for lifting the bucket from its loading situation.

PATRICK GOODMAN.
